UNITED STATES PATENT OFFICE.

CHARLES GIROLAMI, OF CHICAGO, ILLINOIS.

FLYING-MACHINE.

1,124,415.

Specification of Letters Patent.

Patented Jan. 12, 1915.

Application filed April 18, 1910. Serial No. 556,210.

To all whom it may concern:

Be it known that I, CHARLES GIROLAMI, a citizen of the United States, residing at Chicago, in the county of Cook and State of Illinois, have invented certain new and useful Improvements in Flying-Machines, of which the following is a specification.

This invention relates to air ships and has for its primary object to provide an improved construction, combination and arrangement of parts in a flying machine.

One of the objects of the present invention is to provide improved means for maintaining the balance of a flying machine whereby the machine is enabled to right itself automatically when displaced from a position of normal equilibrium.

More specifically stated, one object of this invention is to provide improved means operable by the movement of the machine from normal upright position, for bringing it back to such normal position.

Another object is to provide improved means for maintaining the machine on a substantially level keel as it rises into the air or descends.

Another object is to provide an improved body structure for a heavier-than-air machine.

Other and further objects will appear in the specification and be specifically pointed out in the appended claims, reference being had to the accompanying drawings exemplifying the invention, and in which—

Figure 1 is a top plan view of an air ship constructed in accordance with the principles of this invention. Fig. 2 is a side elevation of the same. Fig. 3 is a front elevation of the same. Fig. 4 is an enlarged detail fragmentary plan view of the automatic equilibrating device. Fig. 5 is a side elevation, parts being shown in section, of the mechanism shown in Fig. 4. Fig. 6 is a section on the line VI—VI, Fig. 4. Fig. 7 is a side elevation of a portion of the bow of the ship showing the adjustable guide vane for changing the elevation. Fig. 8 is a section on the line VIII—VIII, Fig. 1. Fig. 9 is a perspective view of another embodiment of the invention. Fig. 10 is an enlarged perspective view of portions of the air ship shown in Fig. 9. Fig. 11 is an enlarged detail perspective view of portions shown in Figs. 9 and 10.

In the exemplification of the invention shown in the drawings, the flying machine

consists of a long slender boat-shaped body 1, said body being inclosed throughout by a light sheathing of any suitable material, such as aluminum, specially-prepared silk or the like, with the exception of the central upper portion which is open for the ingress and egress of passengers and freight. Mounted on the body 1 is a pair of laterally projecting wing planes 2, 3, each of said planes being provided with a plurality of movable portions illustrated in the present exemplification by vanes 4 and 5, pivotally mounted at the front of said wings and the vanes 6 and 7 pivotally mounted on the lateral edges of said wings said vanes being respectively provided with projecting arms connected above by wires to the wires 35, 36, and below with wires 39 and 40 (see Figs. 1 and 4). Extending longitudinally of the body 1 and preferably rearwardly from the winged planes 2 and 3, is a tail plane 8 provided with laterally projecting portions 9 and 10, and with movable vanes 11 and 12 pivotally connected with the frame of said portions 9 and 10. The vanes 4 and 5 are connected in a manner to be hereinafter pointed out with a swinging carrying member or pendulum in such manner as will adapt said wings to right the machine to a normal position of equilibrium when it is displaced therefrom by reason of a gust of wind or other cause. In a similar manner, the vanes 11 and 12 are also connected with said pendulum or carrying member to right the machine in the event of its pitching into a position at an angle with the horizontal. On the forward end of the air ship is mounted an angularly movable guide vane or aeroplane 13 which is adapted, in a way to be pointed out, to be moved into different positions to guide the air ship upwardly or downwardly. For propelling the air ship it may be provided with one or more engines, such as are indicated at 14 and 15, which engines connect by suitable shafts 16, 17, with propellers 18, 19.

Referring now to Fig. 2, the wings 2 and 3 of the flying machine are each provided with a substantially flat portion 20 and a drooping rearwardly extending portion 21, said drooping portion as shown best in Fig. 3 being deflected downwardly to the greatest extent at points adjacent to the body of the air ship. As shown in Figs. 2 and 3, a wheel 22 on the end of a resiliently and pivotally mounted lever 23 serves to support

the rear end of the ship while on the ground. In the same way a pair of supporting wheels 24 on the ends of two pivotally and resiliently mounted levers 25 serve to bear up 5 the front end of the machine when on the ground, said levers 25 being brought together and provided with an auxiliary carrying wheel 26 which, when the machine descends, is swung around onto the ground to 10 aid in supporting the descending weight thereof. Toward the attainment of one of the objects of this invention, the flying machine is provided with a carrying member suspended in such a manner as to permit a 15 relative movement laterally or longitudinally under the shifting positions of the aeroplane. In order to provide automatic means for righting the machine after it has assumed an abnormal position and to make 20 said means operative by the movement into such abnormal position, the movable stabilizer vanes 4 and 5, and 11 and 12 are operably connected to said carrying member.

As best shown in Figs. 4 and 5 the carrying member according to the preferred embodiment of this invention consists simply of a pendulum bar 27 which is pivotally mounted in a head block 28, said head block being in turn pivotally mounted preferably 25 on an axis perpendicular to the pivotal axis of the bar 27 and in members rigidly fixed to the frame work of the ship. In this manner any weight carried by the pendulum bar 27 is connected with the frame 30 work of the aeroplane with a universal movement permitting said bar to swing laterally or longitudinally to assume a vertical position under any movement of the aeroplane. In this exemplification of the invention an 35 engine 15, which may be of any suitable construction, is connected up to drive the rear propeller 19 by means of an extensible shaft 17 comprising telescoping sections 30 and 31, said shaft being connected at either end 40 by universal couplings 32 and 33. The pendulum bar 27 is extended upwardly to provide a lever arm 34 to the extremity of which are secured cords 35 and 36 forming a flexible connection between the lever arm 34 45 and each of the movable vanes 4 and 5 respectively. To adapt the pendulum bar 27 to alter the positions of the vanes 4 and 5 when there is a rolling movement of the aeroplane, said vanes are provided with 50 rods or levers 37, 38, which pass normally through said vanes and are secured thereto, the upper outer ends of said rods being secured to the cords 35 and 36. The depending ends of said rods 37 and 38 are connected respectively with cords 39 and 40, 55 which cords are in turn connected to the pendulum bar 27 below its point of pivotal support. The operating cords 35 and 36, 39 and 40 are mounted in suitable guides 60 along the wings. By this description it will

be noted that when the aeroplane tilts laterally the vanes 4 and 5 will be moved respectively upwardly or downwardly according to whether the wings to which they are respectively attached are above or below normal position, and that the angular positions of said vanes relatively to said wings will tend to right the machine to normal position. On the extremities of a horizontal shaft 41 with which the head block 28 is 70 rigid, are levers 42 and 43 secured on said shaft 41 intermediately of their ends. Both of the vanes 11 and 12 are connected up to move together to right the machine longitudinally so that a description of vane 12 75 as moved by the pendulum will be sufficient. As shown in Fig. 5, there are two operating cords 44 and 45 connecting the extremities of the lever 43 with the extremities of the lever 46 rigidly connected to the vane 12 80 for varying the position of said vane during a pitching movement of the machine. It will be seen by this description that should the machine plunge forwardly, the engine 15 would swing forwardly and throw the 85 vane 12 upwardly, there being thereby produced on said vane 12 a pressure tending to return the ship to normal position.

Referring now to Fig. 7, which illustrates means for raising and lowering the flying 90 machine, the movable head vane 13 is pivotally connected at its forward end by a link 47 to the frame work of the machine. Adjacent the center of said vane 13 is mounted a cross head bar or slide 48 which is slidably 95 mounted in guide ways 49 whereby it is adapted to be reciprocated forwardly and rearwardly to change the angular position of the vane 13. As an example of suitable means for effecting this reciprocation 100 said cross head bar 48 is connected by cords or other flexible connections 50, 51, with a hand operating lever 52 on opposite sides of the pivot 53. By this construction the 105 operator may move the vane 13 into any desired position by operating the lever 52.

Referring now to Figs. 9 and 10, the embodiment shown therein is substantially the same as the embodiment already described with the exception that the automatic means for adjusting the positions of the vanes 4 and 5 and 11 and 12 consists of a platform 54 (see Fig. 10) which is suspended from the framework of the flying 110 machine by a universal connection now to be described. This suspension as illustrated consists of a pair of oppositely disposed stirrups 55, 56, which pass under the extremities of the platform 54, said stirrups being pivotally mounted above, preferably 115 in ball bearings at 57 and 58, carried by members 59 and 60, said members being also mounted in ball bearings within portions that are rigidly connected to the framework of the machine. On the rear member 120

60 are mounted two levers 61, 62, intermediately of their ends, the outer extremities of said levers 61, 62, having attached thereto the cords 63, 64, and 65, 66, for operating 5 vanes 11 and 12. The stirrup 56 is provided above and below its pivotal connection with the cross member 60 with extensions 67 and 68 to which are attached the cords for operating the lateral vanes 4 and 5 as already 10 pointed out.

Referring now to Fig. 9 the auxiliary movable vanes 6 and 7, are pivotally mounted on the outer extremity of the aeroplanes 2 and 3 respectively and connected 15 up in a manner similar to that already pointed out in connection with vanes 4 and 5, to the cords 35, 36, and 39, 40.

The operation of the device will now be understood. Briefly stated, it is as follows: 20 When the aeroplane is sailing along in normal upright position, the engine 15 forming a pendulum depends vertically downwardly and serves to hold the movable vanes 4, 5, 25 6, 7, 11 and 12 in conformity to the surface of the fixed planes by means of the connections hereinbefore pointed out. Should, now, something happen to depress the wing plane 2, the engine 15 would swing toward the wing plane 2 in such manner as to rock 30 the vertical arm 27 (see Fig. 5) to swing the upper end thereof away from the wing 2. This movement results in drawing the wire or cable 36 tight, causing the movable plane 4 to drop downwardly and the edge wing 35 6 to move upwardly, said wings being in positions tending to raise the wing 2 into normal position. At the same time the wire or cable 35 on the right hand side being loosened while the under cable 40 is drawn 40 tight, the movable plane 5 is moved upwardly and the movable plane 7 moved downwardly into positions tending to depress the wing plane 3. It will thus be seen that the weight of the engine acts automatically 45 to right the aeroplane when it is moved out of normal position. In a similar manner, the action is reversed when the tilting is in the opposite direction. Should the flying machine plunge forwardly and downwardly, the engine 15 swings toward the front end of the machine, and causes the upper end of the lever 27 to move backwardly in such manner as to raise the vanes 11 and 12 into dotted line position shown in 50 Fig. 5. This position of the vanes 11 and 12 creates a pressure on the tail plane tending to force it downwardly, and so to maintain the ship on a level keel. If for any reason the tail end of the machine should drop, the action would be exactly the opposite, the movable planes 11 and 12 being thrown downwardly and causing an air pressure tending to move them upwardly again into normal position.

65 What I claim is—

1. In an aeroplane, the combination with a fixed plane, of a propeller, a movable plane, an engine, means for suspending said engine from said fixed plane, said means adapting the engine to swing relatively to 70 said fixed plane and to the propeller shaft, means operatively connecting the engine to said movable plane, and flexible extensible means for operatively connecting said engine to said propeller.

2. In an aeroplane, the combination with a fixed plane, of a propeller, movable planes, an engine support suspended from said fixed plane with a universal movement, said support being operatively connected to said 80 movable planes, an engine on said support, and means operatively connecting said engine to said propeller, said means being extensible and flexible, whereby the engine will swing with respect to the propeller.

3. In an aeroplane, the combination with a fixed plane, of a movable plane for maintaining equilibrium, a propeller, an engine for driving the same, extensible means operatively connecting the engine with the propeller for free swinging movement with respect to the propeller, and automatic means for adjusting said movable plane, said means being controlled by said engine.

4. In an aeroplane, the combination with a fixed plane, of a movable plane for maintaining transverse equilibrium, a second movable plane for maintaining longitudinal equilibrium, a propeller, an engine for driving same, extensible means connecting the 95 engine with the propeller for free swinging movement with respect to the propeller, and automatic means actuated by the weight of the engine for adjusting said movable planes simultaneously and independently.

5. In an aeroplane, the combination with a fixed plane provided with movable portions for equilibrating the ship transversely, of a second fixed plane provided with movable portions for equilibrating the ship 110 longitudinally, a propeller for said aeroplane, a pendulum free to swing in any direction under the action of gravity, said pendulum being connected to each of said moving portions, an engine carried by said 115 pendulum and an extensible connection from the engine to said propeller.

6. In an air ship, the combination with a body frame and wing planes provided with stabilizers, of a head plane slidably and 120 pivotally connected with said body frame.

7. In an air ship, the combination with a body frame and wing planes provided with stabilizers, of a head plane slidably and pivotally connected with said body frame, 125 and means for changing the angular position of said head plane.

8. In an air ship, the combination with a body frame and wing planes provided with stabilizers, of a head plane slidably 130

- 4
- and pivotally connected with said body frame, and manually-operated means for changing the angular position of said head plane.
- 5 9. In an air ship, the combination with a body portion and aeroplanes mounted thereon, of a head plane having a slidable connection along one edge, and a pivotal link connection along another edge with said body portion.
- 10 10. In an air ship, the combination with a body portion and aeroplanes mounted thereon, of a head plane having a slidable connection along one edge, a pivotal link connection along another edge with said body portion, and means for reciprocating the slidably-connected edge.
- 15 11. In an aeroplane, the combination with a fixed plane, of an engine swingingly mounted on said plane, movable planes carried by said fixed plane, a propeller rotatably mounted on said fixed plane, and a telescoping shaft extending between said propeller and engine, said shaft being provided with universal couplings at either end to join the shaft to the engine and propeller respectively, and means for transmitting the swinging movement of the engine to the movable planes.
- 20 12. In an air ship, the combination with a fixed plane provided with movable portions for equilibrating the ship transversely, of a second fixed plane provided with movable portions for equilibrating the ship longitudinally, and a pendulum free to swing in any direction under the action of gravity, the said pendulum being connected to each of said movable portions.
- 25 13. In an air ship, the combination with a fixed plane comprising laterally-projecting wings, each of said wings being provided with an angularly movable portion for directing that wing upwardly or downwardly, a second fixed plane extending longitudinally of the ship and provided with angularly movable portions for adjusting the longitudinal pitch of the ship, and automatic means for actuating said movable portions, the movable portions on opposite wings being moved in opposite directions by said automatic means.
- 30 14. In an air ship, the combination with a fixed plane comprising opposite laterally-disposed wings, each of said wings being provided with angularly movable portions, a rearwardly extending fixed plane provided with movable portions, means depending from said ship and movable in all directions under the action of gravity, and means for connecting said depending means to each of said movable portions, the movable portions of said rearwardly extending plane being moved up and down together to maintain the ship in substantially level keel and the movable portions of said oppositely disposed wings being moved oppositely to maintain a substantially level beam.
- 35 15. In an air ship, the combination with a frame, of a carrying member movably suspended therefrom, and a pair of lateral wings mounted on said frame, each of said wings being provided with a pivotally mounted portion on the outside lateral edge, and a second pivotally mounted portion on the front edge thereof.
- 40 16. In an air ship the combination with a frame, of a carrying member movably suspended therefrom, and a pair of lateral wings mounted on said frame, portions of said wings adjacent the lateral edges being deflectable with respect to the remaining portions, another portion of said wings being deflectable transversely with respect to the first recited deflectable portions.
- 45 17. In an air ship, the combination with the body, of lateral wings drooping rearwardly, a tail plane drooping rearwardly, vanes pivotally connected to said planes, and a carrying member suspended from the body and operably connected to said vanes.
- 50 18. In an air ship, the combination with a body, of wing planes the rear portion only of which droops downwardly and inwardly toward the body.
- 55 19. In an air ship, the combination with a body portion, of wing planes having each a substantially horizontal flat portion and each having a portion drooping inwardly and rearwardly toward the body.
- 60 20. In an air ship, the combination with a body portion, of wing planes having each a substantially horizontal flat portion and each having a portion drooping inwardly and rearwardly toward the body, and a rear plane having a downwardly and rearwardly deflected portion.
- 65 21. In an air ship, the combination with a fixed plane provided with movable portions for equilibrating the ship transversely, of a second plane provided with movable portions for equilibrating the ship longitudinally, and a motor free to swing in any direction under the action of gravity, said motor being connected to each of said movable portions.
- 70 22. In an air ship, the combination of a propeller rotatable about a fixed axis, a motor oscillable about another axis, means for operatively connecting the propeller with said motor, said means including an extensible joint, and movable aeroplanes operatively connected to and partaking of the swinging movement of said motor whereby said air ship is maintained in transverse and longitudinal equilibrium.
- 75 23. In an air ship, the combination of a propeller rotatable about a fixed axis, a motor oscillable about another axis and adapt-

ed for swinging movement with respect to the propeller, a universal and an extensible connection between the propeller and motor, and a movable aeroplane operatively connected to and partaking of the swinging movement of said motor whereby the air ship is maintained in equilibrium.

24. In an air ship, the combination of a propeller rotatable about a fixed axis, a motor oscillable about another axis and adapted for swinging movement with respect to the propeller, a universal and an extensible connection between the propeller and motor, a movable aeroplane operatively connected to and partaking of the swinging movement of said motor whereby said air ship is maintained in equilibrium, said connection also partaking of the swinging movement of the motor.

25. In an air ship, the combination with the main body frame, a motor swingingly suspended therefrom, a rotary element driven by said motor and partaking of its swinging movement, a propeller driving shaft rotatable about an axis fixed with respect to the body frame and with respect to which shaft the motor is adapted to swing, a universal and an extensible connection between said shaft and rotary element, and means actuated by the swinging movement of the motor for maintaining the ship in equilibrium.

26. In an air ship, the combination with a main body frame and a motor swingingly suspended therefrom, a rotary element driven by said motor and partaking of its swinging movement, a propeller shaft rotatable about an axis fixed with respect to the body frame and with respect to which shaft the motor has a swinging movement, a universal connection and an extensible connection between the shaft and the said rotary element, and means actuated by the swinging movement of the motor for maintaining the ship in equilibrium, said connection being operative during the swinging movement of the motor.

27. In an air ship, the combination with a rigid frame, of a propeller driving shaft journalized in said frame, a motor movably suspended from said frame to swing about two intersecting axes, a rotating element

driven by the motor, said element also partaking of the swinging movement of the motor, means extensible connecting said rotary element in driving relation to said propeller shaft, said means being operative during the swinging movements of said motor, and movable aeroplanes partaking of the swinging movements of the motor.

28. In an aeroplane, the combination with a fixed plane provided with movable portions for equilibrating the ship transversely, of a second fixed plane provided with movable portions for equilibrating the ship longitudinally, a propeller for said aeroplane, a pendulum free to swing in any direction under the action of gravity, said pendulum being connected to each of said moving portions, an engine carried by the pendulum, and means operatively connecting said engine and the propeller, said means being extensible and flexible.

29. In an air ship, the combination with a frame, of a carrying member movably suspended therefrom, a pair of lateral wings mounted in said frame, portions of said wings adjacent the lateral edges being deflectible with respect to the remaining portions, another portion of said wings being deflectible transversely with respect to the first recited deflectible portions, and means connecting said deflectible portions with said carrying member.

30. In an air ship, the combination with a frame, of a carrying member movably suspended therefrom, a pair of lateral wings mounted in said frame, portions of said wings adjacent the lateral edges being deflectible with respect to the remaining portions, another portion of said wings being deflectible transversely with respect to the first recited deflectible portions, and means for causing said deflectible portions to partake of the respective swinging movements of the carrying member.

In testimony whereof I have signed my name to this specification, in the presence of two subscribing witnesses, on this 14th day of April A. D. 1910.

CHARLES GIROLAMI.
